UNITED STATES PATENT OFFICE.

THOMAS HUMPHREY, OF NEW BRIGHTON, NEW YORK.

HEAD-REST FOR HAMMOCKS.

SPECIFICATION forming part of Letters Patent No. 355,873, dated January 11, 1887.

Application filed August 23, 1886. Serial No. 211,621. (No model.)

To all whom it may concern:

Be it known that I, THOMAS HUMPHREY, of New Brighton, in the county of Richmond and State of New York, have invented a new and useful Improvement in Head-Rests for Hammocks, of which the following is a specification.

In most hammocks there is employed a hammock-spreader, extending transversely across the hammock, and serving by engagement with the suspension-cords to keep the hammock spread out and prevent it from closing around the body.

My invention relates to head-rests which are supported from the ends of the spreader, and therefore have no direct connection with the hammock proper. It has been proposed to insert through the curved bar which constitutes the spreader, and near each end thereof, a metal eye, from which the end of the head-rest is hung by a triangular wire.

The object of my invention is to provide attachments for the head-rest, which are of such nature that they may be applied directly to the ends of a spreader without having to bore the same, and without having to secure therein, by riveting or otherwise, any eyes or other devices.

In carrying out my invention I apply to each end of the spreader a cap or end piece which has its length transverse to the length of the spreader, and which is constructed with a socket adapted to slip upon the extreme end of the spreader, and from opposite ends of these caps or end pieces the connections extend in pairs to the ends of the head-rest.

The invention consists in novel combinations of parts, which are hereinafter described, and pointed out in the claims.

In the accompanying drawings, Figure 1 is a side view of the end portions of a hammock-spreader and a head-rest supported therefrom and embodying my invention, the flexible connections and the central portion of the spreader being broken away to enable the drawing to be made upon a larger scale. Fig. 2 is a plan of the parts shown in Fig. 1. Fig. 3 represents one end portion of the spreader and a transverse section of the cap or end piece which is secured thereon. Fig. 4 represents an end view of the spreader and a cap or end piece of modified form secured thereon; and

Fig. 5 is a plan of a head-rest which receives through it, at opposite sides, cords or other flexible connections, whereby it is supported, and which may be adjusted on such cords or flexible connections lengthwise thereof.

Similar letters of reference designate corresponding parts in all the figures.

In Figs. 1 and 2 I have shown a slightly different construction of the head-rest supports which are applied to the opposite ends of the spreader; but both the constructions there shown are included in my invention, and are shown in one figure to simplify the drawings. The head-rest may, of course, be supported at both ends by such a system of supports as is shown at the left hand of Figs. 1 and 2, or by the devices shown at the right hand of said figures.

A designates a head-rest, which usually consists of a strip or piece of canvas or other fabric of suitable size, and D designates a spreader, from which the head-rest A is entirely supported. This spreader may consist of a bent bar of wood, either of round or rectangular transverse section, and is provided with holding devices for the suspension-cords of the hammock. These holding devices may be of any suitable character; but in the spreader here represented I have shown dovetailed or undercut notches b for receiving the groups of cords, such notches constituting holding devices, which are formed integral with the spreader, and without the addition to the spreader of other parts. A spreader of this character is shown and described in my pending application for United States Patent, Serial No. 210,772, filed August 13, 1886, and is not claimed as a part of this invention. It will be understood that my head-rest and its supports may be adapted for application to spreaders of any of the kinds ordinarily in use.

C designates caps or end pieces, which are or may be made of cast metal, and which are applied one to each of the ends of the spreader B. In the construction here illustrated, and which I deem preferable, the cap or end piece is constructed with a socket, c, which receives within it the end of the spreader B, the cap being thereby adapted to be readily slipped upon and removed from the end of the spreader without having any permanent connection

therewith. This socket may not extend entirely through the cap C; but the metal of the cap may be continuous over the end of the spreader, as shown at the left hand of Figs. 1 5 and 2 and in Fig. 3; or I may form a slight shoulder upon the end of the spreader, as shown at b' at the right hand of Figs. 1 and 2 and in Fig. 4, and in such case the cap C will be held in proper position by resting upon the 10 shoulder b'.

Flexible connections extend in pairs from each end of the head-rest A to the caps or end pieces, C, and I have shown all the caps or end pieces as provided with eyes c' to receive such connections. 15

As represented at the left hand of Figs. 1 and 2, the connections D are formed by a single cord, which may be of textile material or of twisted wire, or a single stiff wire of proper 20 size might be used. The ends of the cord or wire forming the connection D are tied in perforations or holes s in the head-rest A, and the cord or wire passes from the head-rest through the eyes c' and around the back of 25 the cap or end piece, C, between the eyes. As here shown, the cap or end piece, C, has extending along its back and between the eyes c' a groove or concave seat, c'', which receives the cord or wire D and retains the latter in place. 30

At the right hand of Figs. 1 and 2 I have shown connections D, consisting of spiral springs, which are secured at one end in the perforations or holes s of the head-rest, and 35 are at the opposite end secured in the eyes c' of the cap or end piece, C. The perforations or holes s in the head-rest A may be re-enforced by eyelets inserted therein; or, if desired, a strip of metal may be secured in the hem at 40 each end of the head-rest, as is shown by dotted lines at one end of the head-rest in Fig. 2.

In Fig. 5 I have shown a head-rest, A, which is supported by cords or flexible connections D, and in this figure the connections D not only 45 extend from opposite ends of the head-rest, but also extend through hems e, formed at opposite sides of the head-rest and receiving the cords through them. When the head-rest is thus combined with the connections D it may 50 be adjusted upon them in the direction of their length and in a direction transverse of the hammock, so that it may be brought nearer one side or the other thereof, as may be desired.

55 I am aware that it is not new to support a hammock head-rest by means of a wire hanger at each end, attached by an eye to the spreader near its end, and I do not, therefore, include such a construction in my invention.

5c What I claim as my invention, and desire to secure by Letters Patent, is—

1. The combination, with a hammock head-rest, of caps or end pieces adapted for attachment to the ends of a spreader, so as to stand with their length transverse to the length of 65 the spreader, and cords or flexible connections extending in pairs from the opposite ends of the caps or end pieces to the ends of the head-rest, substantially as herein described.

2. The combination, with a hammock head-rest, of end pieces or caps, each having a socket, whereby it is adapted to slip over the end of the hammock-spreader, so as to be retained with its length transverse to the length of the spreader, and also having eyes at its 75 opposite ends and flexible connections extending in pairs from the eyes at opposite ends of the caps or end pieces to the ends of the head-rest, substantially as herein described.

3. The combination, with a hammock head-rest and flexible connections extending from its opposite ends, of caps or end pieces, each having a socket, whereby it is adapted to slip over the end of a hammock-spreader, and whereby it is retained with its length trans- 85 verse to the length of the spreader, and having at the back a concave seat, c'', for receiving and retaining the flexible connections extending from the end of the head-rest, substantially as herein described. 9c

4. The combination, with a hammock head-rest and flexible connections extending from opposite ends thereof, of the caps or end pieces, C, each having a socket, c, to receive the end of a hammock-spreader, and having 95 eyes c' at opposite ends, and a concave seat or groove, c'', extending along its back between the eyes, substantially as herein described.

5. The combination, with caps or end pieces, C, constructed with sockets, whereby they are 100 adapted to slip over the ends of a hammock-spreader, of cords or flexible connections which are continuous between the ends of the opposite caps or end pieces, and the head-rest supported by the cords or flexible connections 105 and adjustable lengthwise upon them independently of any lengthwise adjustment of the cords or flexible connections themselves, substantially as herein described.

6. The combination, with a hammock head-rest, of end pieces or caps constructed with sockets, whereby they are adapted to slip over the end of a hammock-spreader, and wire springs extending in pairs from the opposite ends of the end pieces or caps, and forming 115 flexible and elastic connections between the ends of the head-rest and the end pieces or caps, substantially as herein described.

THOMAS HUMPHREY.
